(57) **CLAIM**

The ornamental design for a clip-on toothbrush head cover as shown and described.

DESCRIPTION

FIG. 1 is a first perspective view of a clip-on toothbrush head cover, showing my new design;

FIG. 2 is a second perspective view thereof, shown in an open position;

FIG. 3 is a rear elevational view thereof, shown in a closed position;

FIG. 4 is a front elevational view thereof;

FIG. 5 is a top plan view thereof;

FIG. 6 is a bottom plan view thereof;

FIG. 7 is a right-side elevational view thereof; and,

FIG. 8 is a left-side elevational view thereof.

In the drawings, the broken lines illustrate portions of the article and form no part of the claimed design.

1 Claim, 8 Drawing Sheets
